UNITED STATES PATENT OFFICE.

WALTER F. DAHLSTROM, OF MINNEAPOLIS, MINNESOTA.

DESIGN FOR A PAPER WEIGHT OR ANALOGOUS ARTICLE.

Application filed December 2, 1927. Serial No. 24,365. Term of patent 3½ years.

To all whom it may concern:

Be it known that I, WALTER F. DAHLSTROM, a citizen of the United States, residing at Minneapolis, in the county of Hennepin and State of Minnesota, have invented a new, original, and ornamental Design for a Paper Weight or Analogous Article, of which the following is a specification, reference being had to the accompanying drawing, forming part thereof.

In the drawing,

Fig. 1 is a front elevation of a paper weight constituting the design; and

Fig. 2 is a plan view of the same.

What I claim is:

The ornamental design for a paper weight or analogous article, as shown.

WALTER F. DAHLSTROM.
